UNITED STATES PATENT OFFICE.

ALEX WENDELBURG, OF NEW YORK, N. Y., ASSIGNOR TO PITTSBURGH ELECTRIC TOOL COMPANY, OF NEW YORK, N. Y., A CORPORATION OF PENNSYLVANIA.

ELECTRIC HAMMER.

1,250,401.

Specification of Letters Patent. Patented Dec. 18, 1917.

Application filed July 28, 1914. Serial No. 853,784.

To all whom it may concern:

Be it known that I, ALEX WENDELBURG, a citizen of the United States, residing in the city of New York, county of New York, and State of New York, have invented certain new and useful Improvements in Electric Hammers; and I do hereby declare the following to be a full, clear, and exact description of the invention, such as will enable others skilled in the art to which it appertains to make and use the same.

This invention relates to electric hammers adapted for use in chipping, calking, riveting, cutting and other work requiring a rapid succession of blows upon a suitable tool. The invention is directed to the provision of an improved form of electric hammer which is simple in construction, which may be manufactured at low cost, which is so constructed as to permit of cooling it by immersing it in a liquid, which is of comparatively light weight and which possesses such strength and rigidity as will enable it to withstand the continual jarring to which it is subjected in use.

One of the features of the invention resides in so constructing the hammer as will permit of immersing its main body portion in a liquid without danger of injury to the coils or other portions of the structure. By reason of this, provision for a water circulation through or around the structure of the hammer or any other means for preventing overheating is unnecessary. Instead, the operator may have a bucket of water near him and, at intervals, when the use of the hammer is temporarily discontinued, he may place the main body portion of the hammer in the water to the desired extent so as to cool it.

The invention also involves the provision of an improved form of circuit-controlling mechanism whereby the operation of the hammer is governed. This involves the provision of a cavity in the handle of the hammer in which a circuit-breaker of special form is removably mounted, this circuit breaker being operable to open and close the circuit to the coils of the hammer. The construction of the circuit-breaker is such as to

insure a good contact when the operating handle of the switch is moved to the closed position and to minimize the danger of arcing at the terminals by the provision of auxiliary contact surfaces which effect a delayed breaking of the circuit.

The invention also involves numerous other features of improvement in the construction of the hammer whereby great strength, good wearing qualities and ample protection of the parts are obtained. These and other features of the invention will be better understood by reference to the following description taken in connection with the accompanying drawing which shows the preferred embodiment of the invention.

In the drawing, Figure 1 is a central sectional view of a hammer embodying my invention;

Fig. 2 is an enlarged sectional view through the circuit-controlling mechanism;

Fig. 3 is a transverse section of the circuit-controller on line 3—3 of Fig. 2; and

Fig. 4 is a diagram of the circuit connections.

Referring to these drawings, the frame of the hammer consists primarily of a tubular casting 4 and a handle casting 5. The casting 4 is of non-magnetic material, preferably phosphor bronze, and the tubular passage therethrough contains a reciprocating solenoid core or plunger 6, adapted to strike the end of a tool to be inserted through the hollow tool-guide 14, hereinafter mentioned. The casting 4 is provided with radially disposed walls 7, 8 and 9, which provide spaces between them for solenoid coils 10 and 11. These coils are wound in opposite directions and serve to develop magnetic fields which actuate the plunger 6 constituting the core of the solenoid. The coils are inclosed by a casing 12 which is preferably a piece of steel tubing. This tubing and the walls 7, 8 and 9, are of such dimensions that the tubing fits snugly around the walls, and the spaces between the walls 7, 8 and 9, and the casing 12 are completely filled by the coils 10 and 11.

The forward ends of the casting 4 and the casing 12 are connected together by a nozzle 13. For this purpose, the projecting end of 100

the casting 4 is provided with an exterior thread with which the nozzle 13 coacts and the nozzle is formed with a projecting flange adapted to fit tightly over the end of the casing 12, as shown. The forward end of the hammer is provided with a tool guide 14 of slightly smaller internal diameter, so that the plunger cannot slip out. This tool guide is preferably formed to fit into the end 16 of the casting 4 and have threaded engagement with the end of the nozzle 13. By this construction, the forward ends of the casting 4 and the casing 12 are rigidly connected by the nozzle 13 so as to preclude relative movement of these parts, and the nozzle effects such a tight fit with the guide and casing as will preclude the entrance of a liquid between these parts when the forward end of the tool is immersed, in use, or for purposes 20 of cooling.

At the opposite end of the hammer, the central passageway through the casting 4 is provided with an enlargement for a cushioning spring 16 to receive the blow of an 25 impact block 15. A portion of this block 15 lies within the tubular passage through the casting 4 in which the striking plunger 6 reciprocates. The remainder of the block 15 is of larger diameter and lies within the 30 enlargement of the tubular passage. The coiled spring 16 bears at one end upon the block 15, the latter being provided with a peripheral flange 17 encircling the end of the spring so as to hold the latter against 35 lateral movement. Between the larger portion of the block 15 and the wall at the end of the enlarged chamber is a washer 18 of hardened tool steel which receives the blow of the block 15 when the latter is returned 40 by the spring 16. The opposite end of the enlarged chamber is closed by a cap 19 which has threaded engagement with the wall of the casting 4. The exteriorly threaded flange on this cap serves as a retainer coacting with the end of spring 16 to hold the latter in position. This flange and the similar flange 17 on block 15 prevent side motion of the spring so that chafing of the spring upon the walls of its 45 50 closing chamber and consequent lack of uniformity in the action of the spring are prevented.

The casting for the handle 5 has a central opening therethrough in which the rear ends 55 of the casting 4 and the casing 12 are received. For securing these parts together, the casing 12 may conveniently have a sleeve 20 secured thereon by means of rivets and forming a circumferential flange. The tubular end 21 of the handle casting 5 closely incloses the end of the casing 12 and is exteriorly threaded to coact with a ring or collar 22 on which is a lip 23 adapted to engage the flange 20. When the sleeve 22 is screwed

up tightly, the end 21 of the handle casting 65 and the lip 23, both of which closely inclose the casing 12, engage the flange 20 on opposite sides thereof and grip the handle casting 5 to the casing 12. The casting 5 is also 70 interiorly threaded to coact with a threaded plug 24 which fits closely around the adjacent end of the casting 4, its end abutting against a flange 25 thereon. In this way, both the casing 12 and the casting 4 are 75 connected to the handle casting 5 and these 80 connections are such tight ones that they not only afford the necessary degree of strength, but also preclude the passage of water through them.

The plug 24 is provided with a hole 80 through the center thereof as are also the caps 19 and 15. Because of this provision, air may pass freely from the space between the block 15 and the striking plunger 6 as 85 may also any water which enters this space. The plunger 6 is preferably provided with a radial slot from end to end as is shown for guarding against the flow of eddy currents in the core or plunger 6.

The flow of current in the coils of the 90 solenoid is controlled by a switch or circuit-breaker located in a cylindrical cavity formed in the handle casting 5 directly above the grip 55 of the handle where the operator may readily press the button of the 95 circuit-controller with his thumb. The parts of this circuit-controller are located within a tube of insulating material and may all be assembled within this tube before the latter is inserted in its cavity within the handle casting. Also, the parts of this circuit-controller are specially constructed so as to provide for a hard rubbing engagement of the contacting surfaces and a delayed break 100 of the circuit at auxiliary contacts. The construction of the circuit-controlling apparatus is shown more clearly in Fig. 2. In the bottom of the cavity in the handle casting 5 are a washer 26 and block 27 of insulating material both of which are removable held in place by a screw 50, as shown in dotted lines in Fig. 2. In the insulating block 27 are two contacts 28, which have wires connected thereto which pass through 110 a passage 29 formed in the casting 5 and are connected to terminals upon a block 30 of insulating material which is secured upon the casting 4 in the space between the latter and the end of the casing 12. The contacts 28 are adapted to be engaged by the ends 115 of pins 31 located in a cylindrical block 32 of insulating material which is secured in the end of a tube 33 of insulating material of a size adapted to fit snugly within the cavity formed in the casting 5. This block 32 is secured to the tube 33 by one or more pins 34. The opposite ends of the pins 31 are threaded into contacts 35 which are of 120 125

semi-circular form and are secured upon the block 32 directly opposite each other. The ends of these contacts 35 rising from the block 32 are spaced apart and on their adjacent sides they are provided with inclined curved depressions as shown at 26. (See Fig. 3.)

A second block 37 of insulating material is secured in position within the tube 33 and forms a guide for a movable contact carrier 38. This carrier has the contact 39 secured thereon, this contact being in the form of a cup or bell the skirt of which is slotted so as to form a plurality of resilient contact fingers. The contact carrier 38 has a cavity formed therein which receives a spring 42 bearing upon a washer of heat-insulating material resting on the enlarged end 43 of a short rod 44 carrying an auxiliary contact 45. This auxiliary contact is of conical form as shown. The rod 44 is adapted to slide in the opening provided for its reception in the contact carrier 38. The spring 42, being inclosed in a chamber whose walls are of heat-insulating material is correspondingly protected against loss of temper due to the heat of sparking at the contacts when the current is broken. A spring 41 is interposed between the block 37 and a flange 49 of the stem 53 of insulating material having at its top a press button 46. When the parts of the circuit-controller have been assembled within the tube 33 of insulating material, the latter is moved into the cavity in the handle 5 and the end of that cavity is inclosed by a threaded cap 47.

The wires for carrying current to and from the hammer enter the structure through a passage 48 provided in the handle casting 5. A connection block 49 of insulating material carrying three terminals insulated from each other is preferably provided upon the casting 5, at this point, to which block the wires leading to the hammer are connected.

The wiring for carrying current to and from the hammer is illustrated diagrammatically in Fig. 4. By reference to Fig. 4, it will be noted that two of the wires or conductors pass from terminals on the insulating block 49 to the block of insulating material 30, and, from said block 30 are continued by other wires until they are connected respectively to the non-adjacent ends 55 of the coils 10 and 11. The adjacent ends of these coils are connected together, and, from their point of connection, a wire leads to the block 30, and is continued by another wire from the block 30 to one of the contacts 28. From the other contact 28, a wire leads to the third terminal upon the insulating block 49. These connections are such that the connection from the junction of the two coils 10 and 11 to the other side of the

circuit may be opened or closed by the circuit-breaking mechanism located in the cavity of the handle, since this connection is made through the contacts 35 which are connected or disconnected by the bell 39 and auxiliary contact 45. In Fig. 4, the insulating block 30 is shown as provided with individual grooves for the reception of the several wires or conductors referred to. In assembling and dis-assembling the hammer, the wires leading from the insulating block 40 and from one of the contacts 28 to the insulating block 30 can be electrically connected with the continuations of those wires respectively, by means of suitable connecting and disconnecting screws 56, as will be readily understood.

When the button 46 is pressed, the contact 39 and auxiliary contact 35 are moved forward and the latter engages the inclined surfaces 36 upon the contacts 35, so closing the circuit. As the movement of button 46 is continued, the auxiliary contact 45 is moved back relative to the contact carrier 38 thereby compressing the spring 42. As this takes place, the contact 39 moves over the contacts 35 so as to effect an electrical connection between them. By reason of the resiliency of the slotted skirt of the bell-shaped contact 39, a good rubbing engagement of the contact 39 upon the contacts 35 is obtained. Furthermore, the conical form of the auxiliary contact 45 causes the contacts 35 to spread somewhat so that they are forced apart and therefore effect a more intimate engagement with the contact 39. 100

When the pressure on the button 46 is relieved, the spring 41 forces the contact carrier 38 and the contact 39 upwardly so as to interrupt the connection of the contacts 35 by the contact 39. While this is taking place, however, the auxiliary contact 45 does not immediately disengage the contacts 35 for the reason that it is still kept in contact with them momentarily by the spring 42. 105

After the contact 39 has moved away, however, a distance sufficient to clear contacts 35, the contact 45 disengages those contacts so as to break the circuit. As a consequence, whatever arcing there is takes place between the contact 45 and the surfaces 36, and has no effect upon the surfaces of contact between the slit bell 39 and the outer peripheries of the contacts 35, which therefore remain constantly bright and in efficient conductive condition. 110

The circuit-breaker herein described may be readily constructed at low cost by assembling the parts within the insulating tube 33 and thereafter inserting that tube in the cavity in the handle of the hammer. In 115 operation, this circuit-controller serves to close and open the circuit effectively, a good contact of large surface area being insured 120

by the arrangement of the contact 39 to inclose the two contacts 35 and the contact 45 to spread the contacts 35 into hard engagement with the contact 39. The construction described above also permits the tube 33 and the switch apparatus mounted therein, including the contact pins 31, to be readily removed without disconnecting the wires from the contacts 28 with which the pins are adapted to engage when the tube 33 is in place.

It will be noted that the construction of the hammer is such as will permit of cooling it by inserting the whole of the forward portion of the hammer in a cooling liquid. The coils 10 and 11 are so inclosed and the connections between the inclosing parts are such that the entrance of the cooling liquid into the chambers for the coils is precluded.

To further insure this result, the flange 57 is brazed to the shell or casing 12, and a thin asbestos gasket 58 is inserted at the point indicated; in addition to which the screw-threads connecting the nozzle 13 to the end of the casting 4 and to the tool guide 14 may be shellacked before assembling the parts, thereby making absolutely watertight joints.

While the parts of the hammer are connected together with such strength and rigidity that the continual and severe jarring incident to the use of the hammer will not cause the parts to work loose, they may be taken apart by unscrewing collar 22 which permits the handle to be drawn off of the end of casing 12 carrying with it plug 24. The various circuit wires within the handle should have sufficient slack to permit the handle to be drawn off of the end of casing 12 far enough to obtain access to the terminal block 30 from which they may then be disconnected, but since the terminal block is fastened to the frame member 4 the connections between the coils and the terminal block need not be disturbed after having once been made. The tool steel washer 18 which receives the return blow of the block 15 is fixed in position within its cavity, preferably by sweating it in place, in order that it may not follow the upward movement of said block.

What I claim is:

1. An electric hammer comprising the combination of a frame member formed with a tubular portion having walls extending radially outward therefrom and an enlarged chamber at one end of said portion, a striking solenoid core plunger reciprocating in said tubular portion, a spring located in said chamber, an impact block coacting with the spring and plunger and having a portion fitting within the tubular portion of the frame member and an enlarged portion fitting within said enlarged chamber, a cas-

ing inclosing the frame member and fitting 65 against said walls, and a solenoid coil in the space between the casing and the tubular portion of said frame member; substantially as described.

2. An electric hammer comprising the 70 combination of a frame member formed with a tubular portion having walls extending radially outward therefrom and an enlarged chamber at one end of said portion, a striking solenoid core plunger reciprocating in 75 said tubular portion; a spring located in said chamber, an impact block coacting with the spring and plunger and having a portion fitting within the tubular portion of the frame member and an enlarged portion fitting 80 within said enlarged chamber and provided with a flange surrounding the end of the spring, a casing inclosing the frame member and fitting against said walls, and a solenoid coil in the space between the cas- 85 ing and the tubular portion of said frame member; substantially as described.

3. An electric hammer comprising the combination of a frame member of tubular form having a passage therethrough, an 90 enlarged chamber at the end of the passage, a striking plunger reciprocating within the passage, a spring located in said chamber, an impact block coacting with the spring and plunger and having a portion fitting 95 within the tubular portion of the frame member and an enlarged portion fitting within said enlarged chamber and provided with a flange surrounding the end of said spring, a washer through which said impact block extends lying at the bottom of said chamber and adapted to receive the return blow of the block when the latter is returned by the spring, a casing inclosing the frame member and a solenoid coil in the 100 space between the casing and the frame member; substantially as described.

4. An electric hammer comprising the combination of a frame member of tubular form having an enlarged chamber formed 110 in one end thereof, a striking plunger reciprocating within said member, a spring located in said chamber, a cap closing the end of the chamber and coacting with said spring, a casing inclosing said member, a solenoid coil in the space between the casing and said member, a handle secured to the casing and a plug secured to said handle and inclosing the end of said member having the chamber formed therein; and serving to lock said cap against rotation induced by vibration of the hammer; substantially as described.

5. An electric hammer comprising the combination of a frame member of tubular form, a striking plunger adapted to reciprocate in the passage through the frame member, a spring located in said passage, a

- cap closing one end of said passage and co-acting with one end of the spring, an impact member located in said passage and co-acting with the other end of the spring and 5 with the striking plunger, a plug inclosing the end of said frame member and said cap to lock said cap against rotation induced by vibration of the hammer, said cap, said impact member and said plug having openings 10 therethrough, a casing inclosing the frame member and a solenoid coil in the space between the casing and said frame member; substantially as described.
6. An electric hammer comprising the 15 combination of a frame member of tubular form having a passage therethrough and an enlarged chamber at one end of the passage, a striking plunger reciprocating in said passage, a spring located in said chamber, a cap 20 closing one end of said chamber and coacting with one end of the spring therein, an impact member coacting with the other end of the spring and with the striking plunger and having a portion fitting within the 25 passage of the frame member, and an enlarged portion fitting within the enlarged chamber and provided with a flange surrounding the end of the spring with which the impact member coacts, said impact member 30 and said cap each having an opening therethrough, a casing inclosing the frame member and a coil in the space between the casing and frame member; substantially as described.
- 35 7. An electric hammer comprising the combination of a frame member of tubular form, a plunger reciprocating therein, coils encircling the frame member, a casing inclosing said coils, an annular nozzle threaded upon one end of the frame member and 40 brazed to the adjacent end of the casing, a tool guide threaded to the outer end of said nozzle and fitting within the end of the frame member, a gasket clamped between 45 the end of the frame member and said nozzle for preventing the entrance of water past the threaded connection of said nozzle and said frame member, a spring located within the frame member at the other end thereof, an 50 impact member within the frame member between the spring and said plunger, and means for connecting the end of the frame member adjacent to said spring to the casing; substantially as described.
- 55 8. An electric hammer comprising the combination of a frame member consisting of a tube enlarged at one end to form a chamber and radial walls formed on the tube, coils wound on the tube between said 60 walls, a tubular casing inclosing said coils and coacting with said walls, a spring in said chamber, a cap for retaining said spring in place, a plunger reciprocating in said tube, an impact member located between said
- spring and said plunger, a handle secured to 65 said tubular casing, circuit-controlling mechanism located within said handle and connected to the coils and a plug inclosing one end of said chamber and secured to said handle for locking said cap against rotation 70 induced by vibration of the hammer; substantially as described.
9. An electric hammer comprising the combination of a tubular frame member, a plunger reciprocating therein, a solenoid coil on the frame member, a terminal block secured to the frame member, a casing inclosing the coil, permanently attached circuit connections between the terminals on 75 said block and said coil, a handle secured to the casing and frame member having a cavity therein, two contacts located at the base of said cavity, permanently attached circuit connections between said contacts and the terminals on said block, an insulated tube detachably mounted within said cavity, a pair of contacts mounted at the end of said tube, a movable carrier mounted within said tube and provided with contacts adapted to coact with the pair of contacts 80 mounted at the end of said tube, and means whereby said last-named pair of contacts may be detachably connected to the two contacts located at the base of the cavity to 85 permit the removal of said insulated tube and parts associated therewith without disturbing the permanent circuit connections or removing said handle.
10. An electric hammer comprising the combination of a frame member having a tubular portion with an enlarged chamber at one end, a plunger reciprocating in the tubular portion, coils encircling the tubular portion, a casing inclosing the coils, an annular nozzle threaded to one end of the frame member and slipped over the adjacent end of the casing, a tool guide attached to said nozzle and bearing against the end of the frame member, a spring located within the chamber, an impact member having a portion fitting within the tubular portion of the frame member and an enlarged portion fitting within the enlarged chamber, a handle having a portion surrounding said chamber in the end of said casing distant 95 from said nozzle, and means for connecting the handle to said casing; substantially as described.
11. An electric hammer comprising the combination of a frame member of tubular form having a chamber enlarged at one end, a plunger reciprocating within said member, a spring located in the enlarged end of said chamber and coacting with the plunger, a cap attached to said frame member 100 for holding said spring in place, a solenoid coil encircling said chamber, a tubular casing inclosing the coil and member and con-

nected to the member at one end of the hammer, a handle having a tubular end adapted to fit over the casing at the opposite end of the hammer, a sleeve secured to 5 the casing adjacent the tubular end of the handle, a collar adapted to be connected to the tubular end of the handle and having a lip adapted to engage said sleeve, and a closure for the end of the chamber secured

to the handle and engaging the frame member and cap to lock said cap in place; substantially as described.

In testimony whereof I affix my signature, in presence of two witnesses.

ALEX WENDELBURG.
